US0D1082882S

(12) **United States Design Patent** (10) **Patent No.:** **US D1,082,882 S**
(45) **Date of Patent:** **** Jul. 8, 2025**

(54) **FILM LOCATOR**

(71) Applicant: **Shenzhen Hongshengyuanda Technology Co., Ltd.**, Shenzhen (CN)

(72) Inventor: **Chengzhuang Zhong**, Lianjiang (CN)

(73) Assignee: **Shenzhen Hongshengyuanda Technology Co., Ltd.**, Shenzhen (CN)

(**) Term: **15 Years**

(21) Appl. No.: **29/875,647**

(22) Filed: **May 8, 2023**

(30) **Foreign Application Priority Data**

Mar. 6, 2023 (CN) 202330094030.3

(51) **LOC (15) Cl.** **08-05**

(52) **U.S. Cl.**
USPC **D8/14**

(58) **Field of Classification Search**

USPC D8/14, 349, 354; D14/251
CPC B29C 63/0004; B29C 63/02; H02G 1/00;
H04B 1/3888

(57) **CLAIM**

The ornamental design for a film locator, as shown and described.

DESCRIPTION

FIG. 1 is a front perspective view of a film locator, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the film locator, which form no part of the claimed design.

1 Claim, 8 Drawing Sheets
